Franklin H. French

UNITED STATES PATENT OFFICE.

PARIS H. WHEELER, OF WASHINGTON, DISTRICT OF COLUMBIA.

PUZZLE.

SPECIFICATION forming part of Letters Patent No. 447,418, dated March 3, 1891.

Application filed November 11, 1890. Serial No. 371,095. (No model.)

To all whom it may concern:

Be it known that I, PARIS H. WHEELER, a citizen of the United States, residing at Washington, in the District of Columbia, have invented certain new and useful Improvements in Puzzles; and I do declare the following to be a full, clear, and exact description of the invention, such as will enable others skilled in the art to which it appertains to make and use 10 the same, reference being had to the accompanying drawings, and to the letters of reference marked thereon, which form a part of this specification.

This invention relates to certain new and 15 useful improvements in puzzles; and it relates more particularly to that class of games or puzzles in which a series of marbles or other movable objects are adapted to be moved about upon a specially-prepared board 20 or table, the object sought being to effect a certain relative arrangement of the movable objects, the movements of which are governed by special rules or regulations.

The present invention has for its object to 25 provide a new and useful puzzle of the character described.

To this end and to such others as the invention may pertain the same consists in the peculiar construction of the board or table, 30 in which a series of annular spaces of different colors are arranged one within the other, each of the said spaces being provided at equidistant intervals with concaved pockets or receptacles, the number of pockets in each 35 of the sections being equal and the center section or space being provided with a central pocket in addition to the pockets in the uniform series.

The invention consists, further, in the use, 40 in connection with the board or table mentioned, of marble corresponding in color with the colors of the sections of the board and corresponding in number with the number of pockets in the regular series of pockets upon 45 the several sections or colors upon the board.

The invention is clearly illustrated in the accompanying drawings, which with the letters of reference marked thereon form a part of this specification, like letters of reference 50 indicating like parts throughout the several views, and in which drawings—

Figure 1 is a plan view of a puzzle embody-

ing my invention, the marbles being shown in the positions in which they are placed in commencing the solution of the puzzle. Fig. 55 2 is a similar view, in which the marbles are shown in the positions which they should occupy when the game or puzzle has been solved. Fig. 3 is a section through the board.

Reference now being had to the details of 60 the invention by letter of reference, A designates a board or table, which is preferably circular, as shown, and B, C, and D represent annular sections or divisions of the surface of the board, the several divisions being of 65 different colors. For instance, we will suppose that the outer ring or division B is red, the next adjacent section C is white, and the central section D is blue.

Each of the sections B, C, and D is provided 70 at equidistant intervals of its circumference with concaved pockets *a*, the number of pockets in each series being the same, and in the present instance being shown as six, though the number may be varied, if desired, 75 it being essential only that the number in each of the divisions of the board should be the same.

In addition to the regular series of pockets at the blue section D at the center of the board 80 is provided with a central pocket *b*.

In arranging the marbles E, F, and G for the solution of the puzzle, the white marbles E are placed in the pockets in the red or outer section, the blue marbles F are placed in the 85 pockets in the next inner or white section, and the red marbles G are placed in the pockets in the inner or blue section D.

The player first takes a red marble out of its pocket and places it in the pocket *b* in the 90 center of the board. He then transfers a white marble to the pocket in the section D which has been vacated. A blue marble is in turn then placed in the pocket vacated by the white marble being removed, and the 95 movement of the marbles is thus continued in regular order, the order of movement of the marbles being red, white, and blue, and this order being continued until all of the red marbles have been transferred to the pockets 100 within the red space upon the board, the white marbles to the white space, and the blue marbles to the blue space, the central pocket *b* being left vacant.

In order to vary the game, any one of the several pockets upon the board may be selected as the one to be left vacant, when the marbles are arranged, instead of the central 5 pocket; or, the marbles may be arranged differently and their movement regulated by other rules.

While I have shown the board as circular, and prefer such form, it is evident that the 10 general form of the board or its sections may be varied without departing from the spirit of my invention—as, for instance, it may be made square or of any desired number of sides, and with colored sections corresponding 15 to the essential feature of my invention consisting in the division of the board into a series of divisions each having either a different color or some distinguishing mark, and each provided with a series of pockets with an 20 extra pocket at the center of the board, in connection with a series of marbles or other movable objects corresponding in color or other distinguishing mark corresponding with the divisions of the board.

25 Having thus described my invention, what I claim to be new, and desire to secure by Letters Patent, is—

1. In a puzzle of the character described, a board or table having its surface divided into 30 a series of sections or divisions, each section or division having a separate color or other distinguishing mark, and each provided with a series of pockets, the number of pockets in

each section being equal, and an extra pocket being provided in the center of the board or 35 table, of a series of movable objects bearing colors or other distinguishing marks corresponding with the colors or marks of the sections of the board or table, substantially as described, and for the purpose specified.

2. In a puzzle of the character described, a board or table the surface of which is divided into a series of divisions or spaces arranged one within the other, each of the divisions or sections being of a different color, and each 40 45 provided with a series of pockets, substantially as and for the purpose specified.

3. The herein-described puzzle, the same consisting of a board or table the surface of which is divided into a series of divisions or 50 sections arranged one within the other, and each having a different color or other distinguishing mark, and each provided with a series of pockets, the central section having an extra pocket at the central point upon the 55 board, and a series of marbles or other movable objects having colors or other distinguishing marks corresponding with the colors or marks of the sections of the board or table, substantially as and for the purpose specified. 60

In testimony whereof I affix my signature in presence of two witnesses.

PARIS H. WHEELER.
